CHECKER-BRICK

Truman H. Kennedy, McKeesport, Pa., assignor
to National Tube Company, a corporation of
New Jersey

Application May 29, 1947, Serial No. 751,241

6 Claims. (CL 263—51)

1
This invention relates to checkerbrick for hot blast stoves and the like.

Due to the conditions under which hot blast stoves operate, the checkerbrick forming the interior thereof are subjected to severe stresses and strains. This can be realized from the fact that such stoves are as large as 22 ft. in diameter and 115 ft. in height; moreover, the interior temperature ranges from 250° F. at the bottom to as much as 2500° F. at the top. During operation of the stoves, there is a blast of air passing through the stoves at pressures of about 18 lbs. per square inch. In addition to these internal physical conditions, the stoves are subject to extremes of outside atmospheric temperature and at times high winds. As a result of these internal and external physical conditions, the structure alternately contracts, expands and thereby tends to twist and distort the refractory checkerbrick so that they lose their original alignment. Due to years of experience, it has been amply demonstrated that the so-called basket-weave pattern of checkerbrick is most conducive to resisting this tendency to twist and distort the brick work from its original alignment and, at the same time, provides the necessary strength to support the large mass of bricks.

The high temperatures ranging up to 2500° F. before noted, actually softens at least the exposed surfaces of the refractory bricks and, if the brick is not sufficiently thick, the heat may penetrate the interior thereof sufficiently to cause the brick to become completely plastic and deformed. Accordingly, the bricks should be of such thickness that the interior thereof will not become softened as a result of the high temperatures to which the surfaces or flue areas are exposed. In addition to the foregoing, consideration should be given to the provision of maximum heating surface consistent with the brick thickness. It is likewise desirable to have small flues for use with cleaned blast furnace gas in order to provide greater heat transfer efficiency.

It is accordingly an object of the present invention to provide a form of checkerbrick that can be laid in basket-weave pattern to achieve maximum stability and which at the same time provides maximum heating surfaces together with maximum heat transferring qualities without sacrifice of strength.

It is a further object to provide a form of checkerbrick which can be made by molding and which is efficient and economical in use.

The foregoing and further objects will be apparent from the following specification when

2
read in conjunction with the attached drawings, wherein:

Figure 1 is a plan view, partly in section, of a hot blast stove containing checkerwork formed of the checkerbrick of my invention;

Figure 2 is an isometric view of the preferred embodiment of my improved checkerbrick;

Figure 3 is an isometric view of basket-weave checkerwork formed from the checkerbrick shown in Figure 2;

Figure 4 is a side elevation of the brick;

Figure 5 is a vertical section on line V—V of Figure 4;

Figure 6 is an enlarged plan of a section of checkerwork;

Figure 7 is an enlarged plan of a section of checkerwork composed of a modified form of checkerbrick; and

Figure 8 is an isometric view showing two of the bricks of Figure 7 in abutting relationship.

Referring more particularly to the drawings, the numeral 2 designates the preferred form of checkerbrick of my invention. The brick is substantially a rectangular parallelepiped having vertical concave end portions 4 which are in effect quarter segments of cylinders. A space 6 is provided between the concave portions which is substantially equal to the thickness of the brick. The edges 8 of the concave portions are relieved at angles of 45° relative to the ends 10 of the brick or, in case of the inner edges, 45° to a plane normal to the flat inner surfaces 6. Thus, when the bricks are laid in basket-weave pattern with the ends of the bricks abutting the flat mid-surfaces 6 of the adjacent brick, circular vertical flues 12 are formed.

To provide increased heating surfaces and heat transfer efficiency, the flues 12 are provided with helical grooves 14. These grooves are in the form of double threads generated on the inside of a cylinder and are provided in the following manner. Each of the concave surfaces 4 is provided with two groove segments 16 which are quarter segments of a helix. These groove segments extend upwardly from left to right on both the front and back surfaces of the brick at an angle of approximately 43° to the vertical axis of the brick. That is to say, the grooves start upwardly from left to right on the front surface of the brick so that whichever surface is viewed, the groove segments are so disposed. Actually to achieve this effect, the groove segments on the rear surface are oppositely inclined with respect to the grooves on the front surface. There are 55 two groove segments on each concave surface

and the upper left and lower right hand corners of each concave surface are partially grooved as at 18 to provide smooth junctures of the groove segments when the bricks are superposed in conventional basket-weave pattern.

In a preferred size, the brick may be 9" long by 6" high by 3" thick. This latter measurement is extreme in thickness as measured from the outer tips of the concave segments. At the mid-portion or minimum thickness, the brick is approximately 2" thick. This forms flues approximately 3 1/2" in diameter and with the grooves .728" deep by 1/64" wide provides 1005 square inches of heating surface for each cubic foot of stove volume. Without the grooves, the circular flues would provide only 634 square inches of heating surface. Thus, it is seen that the grooves result in a 58% increase in heating surface. Due to the grooves being oppositely inclined, the bricks are only appreciably reduced in cross section at the places where the grooves cross. This is such a small area that the effect on the brick strength is negligible.

This brick can be readily made by molding. By providing draft on the grooves, the mold and brick can be separated as is done in regular iron molding practice. When laid in the familiar basket-weave pattern, the lateral grooves form a series of continuous helices, extending throughout the full length of the flues. The blast air passing under pressure upwardly through the flues assumes a rotary spinning action conforming to the helically grooved surfaces of said flues, thus creating a continuous whirlwind throughout each flue.

Since the air spins while rising, it contacts a much greater surface of the hot refractory than when moving through straight smooth passages of flues. The effect of this rotary spinning action of the air intimately contacting the heating surface of the flues is to considerably increase the transfer of heat from the refractory to the air.

Likewise, a similar rotary spinning action is imparted to the hot gases in their descent through the flues and an increased transfer of heat from the hot gases to the refractory is attained.

In Figures 7 and 8, I have shown a modification of the checkerbrick of my invention. This brick designated generally by the numeral 40 is a rectangular parallelepiped which is laid in basket-weave pattern to form square flues 42. As in the preferred embodiment, a swirling or helical flow is imparted to gas directed through the flues by helical-like grooves 44. The bricks 40 have grooved portions 46, 46' on both faces adjacent both ends thereof with a plain intermediate portion 48 on both faces. In laying the brick in basket-weave pattern, the ends of the brick abut the mid-portions 48 of adjacent bricks. Each of the groove portions has three grooves 50, 52 and 54, which slant upwardly from left to right at an angle of about 45° to the vertical throughout the major portion thereof. Grooves 50 and 52 have a short portion 58 adjacent the intermediate portion 48 which is parallel to the longitudinal axis of the brick. It is noted that grooves of the left hand face 46' are reversed with respect to those of the right hand face 46. That is, intermediate groove 50 is at the bottom and short groove 54 is at the top on the left hand corner whereas 54 is at the bottom and 50 at the top of the right hand face. Thus, if surface 46' and grooves were pivoted 180° around

a pivot at the center point of the bricks, the grooves thereof would be directly superposed over the grooves of face 46. The grooves on the rear faces are exactly oppositely inclined with respect to those on the front face so that if the brick is pivoted on its vertical axis, the face in front will appear the same no matter which of the two faces is being viewed.

A preferred size of this brick is 9" long by 6" high by 3" thick. When laid in basket weave, this produces a 3" square flue 42. The grooves may be 3/4" wide by 3/4" deep and spaced on 3" centers measured on the vertical. Each groove makes one turn in 12". This brick provides 1,157 square inches of heating surface for each cubic foot of stove volume, whereas the same brick without the grooves provides only 576 square inches of heating surface per cubic foot of stove volume. Thus, the grooves provide a 100% increase in heating surface.

While I have shown and described two specific embodiments of my invention, it will be understood that these embodiments are merely for the purpose of illustration and description and that various other forms may be devised within the scope of my invention, as defined in the appended claims.

I claim:

1. A substantially rectangular parallelepipedic checkerbrick adapted to be laid in basket-weave pattern to form vertical flues characterized by segmental slanting grooves on the upright front and back faces adjacent the ends thereof, the grooves in said front and back faces being oppositely inclined, said segmental grooves combining to form substantially continuous helical grooves of the same rotation around all of said flues.

2. A substantially rectangular parallelepipedic checkerbrick adapted to be laid in basket-weave pattern to form vertical flues, said brick having slanting segmental grooves adjacent the ends of front and back faces thereof, the grooves in said front and back faces being oppositely inclined, the mid-portion of said faces having uninterrupted surfaces, the size of said uninterrupted surfaces being substantially the same as the end faces of the said brick, the angularity of the slant of said segmental grooves being such that substantially continuous helical-like grooves of the same rotation are formed thereby when said brick is laid in basket-weave pattern.

3. A substantially rectangular parallelepipedic checkerbrick adapted to be laid in basket-weave pattern, said brick having oppositely disposed vertically extending concave portions on the front and back faces adjacent both ends thereof, the surfaces of said concave portions comprising substantially quadrants of a circle and flat portions intermediate said concave portions, said concave portions combining to form circular flues when said brick is laid in basket-weave pattern.

4. A substantially rectangular parallelepipedic checkerbrick adapted to be laid in basket-weave pattern, said brick having vertically disposed concave cylindrical quarter segments on the front and back faces adjacent both ends thereof, flat portions intermediate said concave portions, segmental grooves in said concave portions, said grooves combining to form continuous grooves around the flues formed by said concave portions when said brick is laid in basket-weave pattern.

5. A substantially rectangular parallelepipedic checkerbrick adapted to be laid in basket-weave pattern, said brick having vertically disposed

concave cylindrical quarter segments on the front and back faces adjacent both ends thereof, flat portions intermediate said concave portions, angularly disposed segmental grooves in said concave segments, said segmental grooves combining to form substantially continuous helical grooves around circular flues formed by said concave segments when said brick is laid in basket-weave pattern.

6. A substantially rectangular parallelepipedic checkerbrick adapted to be laid in basket-weave pattern, said brick having vertically disposed concave cylindrical quarter segments on the front and back faces adjacent both ends thereof, the edges of said concave segments being beveled, flat portions having uninterrupted surfaces intermediate said concave portions, angularly disposed thread-like segmental grooves in said concave segments, the grooves in said front and back faces being inclined in opposite directions, said segmental grooves combining to form sub-

stantially continuous thread-like grooves around circular flues formed by said concave segments when said brick is laid in basket-weave pattern.
